(57) **CLAIM**

The ornamental design for a flexible container, as shown and described.

DESCRIPTION

FIG. 1 is a front and side perspective view of a first embodiment of our flexible container;

FIG. 2 is a front elevational view thereof;

FIG. 3 is a rear elevational view thereof;

FIG. 4 is a left side elevational view thereof, the right side being a mirror image thereof;

FIG. 5 is a top plan view thereof;

FIG. 6 is a bottom plan view thereof;

FIG. 7 is a front and side perspective view of a second embodiment of our flexible container;

FIG. 8 is a front elevational view thereof;

FIG. 9 is a rear elevational view thereof;

FIG. 10 is a left side elevational view thereof, the right side being a mirror image thereof;

FIG. 11 is a top plan view thereof;

FIG. 12 is a bottom plan view thereof.

FIG. 13 is a front and side perspective view of an embodiment of our flexible container;

FIG. 14 is a front elevational view thereof;

FIG. 15 is a rear elevational view thereof;

FIG. 16 is a left side elevational view thereof;

FIG. 17 is a left side elevational view thereof;

FIG. 18 is a top plan view thereof; and,

FIG. 19 is a bottom plan view thereof.

The features shown broken lines in the drawings are for the purpose of illustrating environmental structure, and form no part of the claimed design.

1 Claim, 14 Drawing Sheets
